(57) **CLAIM**

The ornamental design for a wall mount for hair dryer, as shown and described herein.

DESCRIPTION

FIG. 1 is a perspective view of a wall mount for hair dryer showing a new design.

FIG. 2 is a front view thereof.

FIG. 3 is a rear side view thereof.

FIG. 4 is a left side view thereof.

FIG. 5 is a right side view thereof.

FIG. 6 is a top plan view thereof.

FIG. 7 is a bottom plan view thereof.

FIG. 8 is a right side view thereof showing in use view attached to the wall.

FIG. 9 is a right side view thereof showing in use view before coupling with the hair dryer; and,

FIG. 10 is a right side view thereof showing in use view after coupling with the hair dryer.

The broken lines (dotted lines) are used to illustrate features of the article which form no part of the claimed design.
